PRESSER FOOT

William W. Ray, Albuquerque, N. Mex.

Application November 26, 1938, Serial No. 242,583

2 Claims. (Cl. 112—235)

My invention relates to improvements in presser feet for sewing machines.

The principal object of the invention is to provide a presser foot which may be attached to the presser foot bar on present day sewing machines for use in right and left cording, thereby obviating the necessity for having two, right and left, presser feet for these operations.

Another object is to provide a presser foot for the above purpose which is adapted for compensating movement in sewing over heavy seams so that it is unnecessary to pull the work through by hand.

To the accomplishment of the above, and subordinate objects presently appearing, a preferred embodiment of my invention has been illustrated in the accompanying drawing, set forth in detail in the succeeding description, and defined in the claims appended hereto.

20 In said drawing:

Figure 1 is a view in side elevation illustrating my improved presser foot attached to the presser foot bar,

25 Figure 2 is a view in top plan of the presser foot detached,

Figure 3 is a view in transverse section taken on the line 3—3 of Figure 2, looking in the direction indicated by the arrows, and

30 Figure 4 is a view in longitudinal section taken on the line 4—4 of Figure 2, looking in the direction indicated by the arrows.

Referring to the drawing by numerals, in the illustrated embodiment thereof, the presser foot of my invention comprises an elongated foot member 1 having upwardly inclined opposite ends 2 and 3, the former slightly longer than the latter and for facilitating passage of the work 4 thereunder in the usual manner and the throat plate represented at 5. On the top face of the foot member 1, adjacent the shorter end 3 thereof, is a pair of laterally spaced upstanding lugs 6 apertured to one side of the vertical center thereof, as at 7, to receive a pivot pin 8 by means of which said member is pivoted for vertical movement on the lower squared end 9 of a post 10, the pin 8 being located to one side of the vertical center of the lugs 6, and post 10, so that said member is balanced to normally gravitate into a horizontal position on the pin 8 when the parts are elevated.

50 The post 10 is suspended, by means presently described, from a bracket 11 comprising a vertically elongated socket part having side walls 12 extending at right angles from a web 13, and a cross bar 14 connecting the free edges of said

5 walls 12, the bracket 11 being so constructed that it fits loosely between said web and bar and an adjusting screw 15 is rotatably mounted at its opposite ends in said walls 12 and threaded through said post. A knurled head 16 is removably attached to one end of the adjusting screw 15 as by a pin 17. The web 13 and bar 14 prevent the post 10 from swinging on the adjusting screw 15.

The described socket has extended from the web 13 thereof, adjacent one side wall 12, a rectangular flange 18 adapted to fit against a side 10 of the usual presser foot bar 19 and provided with a pair of keeper lugs 20 extending from the upper and lower corners thereof, respectively, the web 13, flange 18 and lugs 20 fitting sidewise against the lower end of said bar 19. A set screw 15 21 extending through said end of the bar 19 and into a central aperture 22 in the flange 18 provides for clamping said flange against said bar in which position the web 13 and lugs 20 engage opposite sides of said bar 19 and prevent the bracket 11 from tilting thereon.

As will now be seen, the bracket 11 and screw 15 suspend the post 10 from the presser foot bar 19 so that by manipulation of the head 16, and thus the screw 15, the post 10, together with the 25 foot member 1, may be adjusted laterally of the presser foot bar 19 in opposite directions, respectively, to adjust said member 1 into different set positions, as desired and in accordance with operating requirement. Under feed of the work 30 4 in the usual manner, the foot member 1 will operate against the work and swing on the pin 8 to ride over heavy seams.

By attaching the flange 18 to opposite sides of the presser foot bar 19, the position of the device may be reversed so as to locate the foot member 1 at opposite sides of the presser foot bar 19 for right and left cording operations.

The foregoing will, it is believed, suffice to impart a clear understanding of my invention. 40

Manifestly, the invention, as described, is susceptible of modification without departing from the inventive concept and right is herein reserved to such modifications as fall within the scope of the subjoined claims.

45 What I claim is:

1. A presser foot assembly for attachment to the presser foot bar of a sewing machine comprising a socket member including a back, a pair of laterally spaced sides extending at right angles 50 from said back, a flange on said back extending oppositely to said sides and offset from the vertical center of the back, means to attach the flange to said bar, a screw extending laterally through said sides, a post threadedly engaged with and 55

depending from said screw below said socket, and a foot member on the lower end of said post, said post being adjustable laterally of said socket under manipulation of said screw.

- 5 2. A presser foot assembly for attachment to the presser foot bar of a sewing machine comprising a socket member including a back, a pair of laterally spaced sides extending at right angles from said back, a flange on said back extending oppositely to said sides and offset from the

10

vertical center of the back, means to attach the flange to said bar, a screw extending laterally through said sides, a post threadedly engaged with and depending from said screw below said socket and laterally adjustable therein upon the manipulation of said screw, and a foot member on the lower end of said post, said foot member being pivoted on said post for vertical swinging movement.

WILLIAM W. RAY. 10
